Primary Examiner — Sandra S Snapp*Assistant Examiner* — Ieisha N Price(74) *Attorney, Agent, or Firm* — Warner Norcross + Judd, LLP(57) **CLAIM**

The ornamental design for a fastener positioning device, as shown and described.

DESCRIPTION

FIG. 1 is an upper perspective view of the fastener positioning device embodying the new design;

FIG. 2 is a front view thereof, the rear view being a mirror view thereof;

FIG. 3 is a right side view thereof, the left side being a mirror view thereof;

FIG. 4 is a top view thereof; and,

FIG. 5 is a bottom view thereof.

FIGS. 1-5 show features of a fastener positioning device in broken lines. These features are shown for environmental purposes and do not form any part of the claimed design. The broken lines immediately adjacent the solid line portions of the design form the boundary of the design, with the broken lines forming no part of the claimed design.
